UNITED STATES PATENT OFFICE.

THOMAS BOND ROGERSON, OF TOLLCROSS, GLASGOW, SCOTLAND, ASSIGNOR TO THE
CLYDE FURNACE COMPANY ("B") LIMITED, OF GLASGOW, SCOTLAND.

BLAST-FURNACE FOR THE SMELTING OF IRON AND OTHER ORES.

1,090,666.

Specification of Letters Patent.

Patented June 9, 1914.

Application filed December 4, 1912. Serial No. 734,842.

To all whom it may concern:

Be it known that I, THOMAS BOND ROGERSON, a subject of the King of Great Britain, residing at Tollcross, Glasgow, Scotland, have invented certain new and useful Improvements Relating to Blast-Furnaces for the Smelting of Iron and other Ores, of which the following is a specification.

At present, in blast furnaces, it is usual to have a "downcomer" which communicates with the dust-catcher, the entrance to the "downcomer" being arranged below the charging hopper and bell (or cup and cone) and above the level of the charge. When dealing with dusty ores and fuel a very considerable loss at present takes place each time the usual device is opened for charging the furnace owing to the free escape of dust and gases to the atmosphere. Various devices have been proposed to obviate this such as by using rotary chargers and such like but such arrangements are not only expensive but, owing to the great heat, are readily put out of order. Now, under this invention I arrange below the usual charging bell and hopper, a feed hopper preferably in the form of an inverted hollow truncated cone into which the charge drops when the bell is opened, this hopper being preferably made of metal and supported on the brick-work lining of the furnace. The level of the charge is kept at some distance above the bottom of this hopper so as to form a gas seal or closure. Below the hopper I make a series of gas outlets in the side wall of the furnace, these outlets extending upward to a gas main which encircles the furnace at the upper end thereof and may be arranged partly in the brickwork and partly outside the same. The gas main communicates with the downcomer and dust-catcher. The main has a series of explosion holes with doors and also a "bleeder". The gas passes off by the gas outlets and any dust carried thereby passes to the dust-catcher. The bottom of the hopper projects inward some distance from the lining of the furnace so as to give a clear space for the passage of the gas to the outlets. By this arrangement I not only insure that dust and gases shall not escape freely as before, but I also insure that they shall all be conveyed to the downcomer and dust catcher. Further the hopper prevents the materials, when

being charged, striking against the brick-work lining of the furnace and breaking it away and thereby prolongs the life of the furnace. Owing to the level of the charged material being near the mouth of the furnace it obviates a long drop for each fresh charge so that there is less liability of the ore and fuel being broken and further a much better distribution of the charged materials takes place.

In order that the invention may be clearly understood I have hereunto appended explanatory sheets of drawings which show the upper part of a blast furnace as constructed in accordance with my invention.

Figure 1 is a view partly in section and partly in elevation, while, Fig. 2 is a plan.

Referring to the drawings:—*a* is the furnace, *b* the usual brick-work lining, *c* the "down-comer", *d* the dust catcher, *f* the charging bell or cone, *g* the charging hopper or cup and *h* the usual arrangement for operating the bell.

It will be seen that, under my invention I arrange below the charging bell and hopper *e*, *g*, a hopper *i* which is or may be made of metal and supported by the brick work at *j* which at this point overhangs toward the center of the furnace. The lower end *i'* of this hopper projects inward some distance from and below the brick-work at *j* so as to leave an annular space *p* therebetween for the free passage of gas to upwardly extending gas outlets *k*, the natural tendency of the charge to assume a concoidal shape also assisting in the formation of such a passage. The outlets *k* are made in the wall of the furnace and the mouths thereof are arranged below the bottom of the hopper *i* while their upper ends communicate with a gas main *e* which latter encircles the furnace at the upper end thereof and, as shown, may be arranged partly inside and partly outside the brick-work.

l are explosion holes with the usual doors or covers while *m* is a bleeder.

o are steam and gas outlets from above the hopper *i* to the gas main *e*. The gas passes off by the gas outlets *k* into the main *e*. These outlets are not liable to be choked, as the charge is directed by the hopper *i* inward and away from the mouths of the openings.

Having now fully described my invention

what I claim and desire to secure by Letters Patent is:—

1. A blast furnace having a charging device, a hopper arranged below the charging device and extending downwardly below the normal level of the charge, a gas main above said hopper and surrounding the upper part of the furnace and arranged partly at the outside thereof and a series of gas outlets 10 extending upwardly through the wall of the blast furnace from below said hopper to the gas main.
2. A blast furnace having a charging device, a hopper below the charging device, a 15 gas main above said hopper, a series of gas outlets extending upwardly through the wall of the blast furnace from below said hopper to the gas main and a number of steam and gas outlets extending from above the hopper 20 to said gas main.
3. A blast furnace having a charging device, a hopper below the charging device and supported by the inner wall of the furnace, said hopper projecting downwardly and inwardly from said wall so as to leave an annular space between the wall and the lower end of the hopper, a gas main and a series 25 of gas outlets communicating with said annular space and said gas main.
4. A blast furnace having a charging device, a hopper below the charging device and supported by the inner wall of the furnace, said hopper projecting downwardly and inwardly from said wall which latter over- 30 hangs toward the center of the furnace, the

hopper projecting downwardly and inwardly from said overhanging part in such manner as to leave an annular space between the wall and the lower end of the hopper, a gas main and a series of gas outlets communicating with said annular space and said gas main. 40

5. A blast furnace having a charging device, a hopper below the charging device and supported by the inner wall of the furnace, 45 said hopper projecting downwardly and inwardly from said wall so as to leave an annular space between the wall and the lower end of the hopper, a gas main partly in the wall of the furnace and a series of 50 gas outlets communicating with said annular space and said gas main.

6. A blast furnace having a charging device, a hopper below the charging device and supported by the inner wall of the furnace, 55 said hopper projecting downwardly and inwardly from said wall so as to leave an annular space between the wall and the lower end of the hopper, a gas main partly in the wall of the furnace, a series of gas outlets 60 communicating with said annular space and said gas main and a number of explosion holes in said gas main.

In testimony whereof I affix my signature in presence of two witnesses.

THOMAS BOND ROGERSON.
